UNITED STATES PATENT OFFICE.

MORRIS F. FINKELSTEIN, OF NEW YORK, N. Y.

SHADE-HOLDER.

1,163,519.

Specification of Letters Patent.

Patented Dec. 7, 1915.

Application filed February 20, 1914. Serial No. 819,970.

To all whom it may concern:

Be it known that I, MORRIS F. FINKELSTEIN, a citizen of the United States, and a resident of the city of New York, borough 5 of the Bronx, in the county of Bronx and State of New York, have invented a new and Improved Shade-Holder, of which the following is a full, clear, and exact description.

This invention relates to holders for the shades or globes of lighting fixtures, and has reference more particularly to a device of this class which comprises a body adapted to be associated with the lighting fixture, 10 and having a shade-receiving ring, a band adapted to encompass a part of the shade to hold the same relatively to the ring, and means for tightening the band and for securing it; the ring having a part engaging 15 the band and serving to guide and hold the same when it is being operated.

The object of the invention is to provide a simple, strong and durable holder for glass or other shades and globes generally 20 used with lighting fixtures such as incandescent lamp sockets or the like, which can be very easily and quickly manipulated to secure a shade in position or to release it, which is adjustable and can be used with 25 shades or globes of different sizes, which very firmly holds the shade or globe against accidental displacement, and yet will not in any way mar or otherwise injure the same, and which may be incorporated in devices of 30 different shapes, sizes, proportions and ornamental design.

The invention consists in the construction and combination of parts to be more fully described hereinafter and particularly set 35 forth in the claim.

Reference is to be had to the accompanying drawings forming a part of this specification, in which similar characters of reference indicate corresponding parts in all 40 the views, and in which—

Figure 1 is a side elevation of an embodiment of my invention showing a shade for an incandescent light, associated therewith; Fig. 2 is a plan view of the holder, with the 45 securing band released and the shade removed; Fig. 3 is a transverse section on the line 3—3 of Fig. 1; and Fig. 4 is a longitudinal section on the line 4—4 of Fig. 3.

Before proceeding to a more detailed explanation of my invention, it should be understood that while the holder is particu-

larly useful for globes or shades of electric light fixtures it can also be advantageously employed for other purposes in which it is desirable or necessary to secure articles such 60 as shades in brackets or sockets. I am aware that devices of this kind have already been proposed, in which an annular body receives a correspondingly formed part of a shade or globe which is secured therein by means 65 of a ring or band, that can be tightened. My invention however involves certain structural elements which I believe to be novel, and by means of which I have succeeded in producing an exceedingly simple 70 and effective holder which will be described more particularly hereinafter.

Certain of the details of construction form no part of the invention and can be varied in accordance with individual preference 75 and special conditions, without departing from the underlying spirit of the invention.

Referring more particularly to the drawings, I have shown for example, a shade roller having a body 10 which may be spun from brass or otherwise fashioned from material adapted for the purpose. The body has a reduced or constricted neck 11 provided with an internally disposed edge flange 12. The neck is adapted and proportioned to receive an electric light socket, and can be secured thereto in any suitable manner. The body, at the end opposite to the neck 11 has an extension 13 forming a shade-receiving ring into which is introduced the 80 neck end 14 of the shade or globe 15. The latter has the edge 16 at the neck outwardly disposed for a purpose which will be described below. The shade-receiving ring 13 has an inwardly disposed flange 17, as is 85 more clearly shown in Figs. 2 and 4.

Arranged within the ring 13 is a band or strap 18 fashioned from flexible metal or other suitable material. The ring has a part 90 cut away and with the edges 20 upset and formed into teeth or serrations 21. Adjacent to one end of the opening 19 the ring has an opening 22 in which is inserted the end of the band 18, the extremity thereof being passed through the opening 19 and 100 bent inwardly and clamped against the inside of the ring, thereby to secure the end of the band with respect to the ring. At two points located substantially equidistant from the fixed end of the band 18, the ring 105 is provided with a pair of preferably circular openings 23 between which the wall of

the ring is inwardly disposed or offset, as is shown in Fig. 3. The band passes through the openings 23 of each pair and along the offsets. These parts of the ring thus constitute guides and holders for the band, preventing its accidental displacement from the ring, and limiting its lateral movement, though permitting freely its longitudinal movement. In effect, the band, the free end 10 of which passes through the opening 19, thus is disposed in three lengths, each of which is adapted to contact with the neck of the shade, inwardly of the edge 16. Thus when the band is tightened the shade will 15 be securely held within the ring.

At the free end of the band I provide a locking dog or cam 24 having a curved handle 25 by means of which it can be manipulated, and provided with a pair of spaced cheeks 26. 20 These have registering openings 27, in which are received the laterally disposed lugs 28 at the end of the band, so that the band and the dog are movably secured together. In effect the dog is pivoted with respect to the 25 end of the band. The cheeks 26 at their forward extremities have outwardly disposed parts 29 each adapted to engage the teeth 20 of one of the upset sides of the opening 19. The arrangement is such that the dog 30 can be swung or rocked about the parts 29 as a fulcrum when these are engaged with the teeth 20. By swinging the dog so that the handle 25 thereof is inwardly disposed against the ring, as is shown in Fig. 3, the 35 band will be tightened by the cam-like action of the dog. By swinging the dog outward the band can be released. It will be seen that when the dog is in a locking position the tension of the band tends to hold it 40 in this position. The effective compass of the band can of course be varied, depending upon which of the teeth are engaged by the locking dog. Thus the holder is adapted 45 for use with shades having necks of different sizes and proportions. It will also be understood that it is not necessary that the neck of the shade be of circular cross-section. While I have characterized the part 13 of

the holder as a "ring," I do not wish to limit myself to a circular form with respect to 50 this part, as a square or other angular shape may also be employed.

While the holder may be attached to the electric light socket or other lighting fixture in any suitable manner, I prefer to employ 55 a device substantially identical with the means for securing the lamp shade 14 to the holder itself. For this purpose I have found it advantageous to provide the neck 11 with a band 30 and a locking dog or cam 60 31. These parts are disposed and operate exactly as the corresponding elements 18 and 24. The neck 11 is constructed to permit the operation of the band 30 and the dog 24, as has already been described with 65 respect to other corresponding parts.

Having thus described my invention, I claim as new and desire to secure by Letters Patent:—

A device of the class described comprising, 70—a body adapted to be associated with a lighting fixture and having a shade-receiving ring; a shade-encompassing-and-holding band within said ring, said shade-receiving ring having an opening in the lateral surface 75 thereof to one end of which one end of said band is clamped; and a pivoted locking and adjusting dog secured to the other end of said band, said ring having pairs of openings through which said band passes, a part 80 of the ring between said openings being offset, whereby the outwardly projecting parts of the band are flush with the exterior lateral surface of the ring, said ring having a series of teeth at the sides of the opening in the 85 lateral surface thereof which are adapted to be engaged by the dogs substantially as and for the purpose set forth.

In testimony whereof I have signed my name to this specification in the presence of 90 two subscribing witnesses.

MORRIS F. FINKELSTEIN.
